UNITED STATES PATENT OFFICE.

FREDERICK MARGGRAFF, OF AUGUSTA, KENTUCKY, ASSIGNOR TO THE
F. A. NEIDER COMPANY, OF AUGUSTA, KENTUCKY, A CORPORATION
OF KENTUCKY.

CLAMP.

SPECIFICATION forming part of Letters Patent No. 788,545, dated May 2, 1905.

Application filed May 31, 1904. Serial No. 210,492.

To all whom it may concern:

Be it known that I, FREDERICK MARGGRAFF, a citizen of the United States of America, and a resident of Augusta, county of Bracken, 5 State of Kentucky, have invented certain new and useful Improvements in Clamps, of which the following is a specification.

The object of my invention is a clamp for holding a number of sheets of varying thickness firmly together.

Referring to the accompanying drawings, in which like parts are indicated by similar reference-letters wherever they occur in the various views, Figure 1 is a plan view of a 15 clamp embodying my invention in its closed position. Fig. 2 is an inverted plan view of the same. Fig. 3 is a side elevation of the same in its closed position. Fig. 4 is a similar view in the open position. Fig. 5 is a 20 detail plan of the straight jaw of the clamp, the dotted lines showing one of the lugs before it is bent up to its final position. Fig. 6 is an inverted detail plan view of the curved jaw of the clamp. Fig. 7 is a perspective view of 25 the locking-lever.

Referring to the parts, the clamp consists of a straight jaw A and a curved jaw B, which are hinged together at one end *a*. Straight jaw A has upon its sides lugs *a'* *a''*, which are 30 formed integral with it and bent up from its sides, as shown in Fig. 5. These lugs *a'* *a''* support a retaining-bar C, below which plate A has a central perforation *a'*. Curved jaw B has a central slot *b*, across which a fulcrum-pin *b'* is secured. Upon pin *b'* a locking-lever 35 D is journaled. Locking-lever D has a downwardly-projecting arm *d*, with a cam-shaped face *d'* and an outwardly-projecting actuating-arm *d''*. Face *d'* has a transverse rib *d'''*.

When the jaws A and B are brought toward 40 each other, the arm *d* engages the retaining-bar C. The cam is made of a shape such that the swinging downward of the arm *d''* draws the jaws more tightly together. Rib *d'''*, engaging bar C, locks the jaws in position. 45 Should the sheet or sheets to be engaged by

the jaws be of ordinary thickness, the jaw B retains its normal shape, when the locking-lever D is thrown to its closed position and clamps the sheet firmly between the jaws. 50 Should the sheets be of considerable thickness, when the locking-lever D is thrown to its closed position the curve in the jaw B flattens somewhat to accommodate the increased thickness. Thus my clamp will grasp sheets 55 of varying thickness and hold them firmly, the cam upon the arm *d* serving to prevent the locking-lever's slipping after it has once been thrown to its closed position until the arm *d''* is raised. The contacting face of the 60 jaw A is preferably scored, so as to roughen it and enhance the gripping action of the jaws upon the sheets.

There are various uses to which my invention may be put. It may be used for holding 65 sheets of paper together, and it may be used for holding carriage-curtains. For instance, by securing the clamp upon the backstay of a carriage-top the clamp would form a most convenient means for holding the back curtain 70 in place, since it would hold the curtain firmly even though it did not have a large bite thereon, and thus its gripping would not be destroyed by a shrinking in the curtain.

What I claim is—

1. In a clamp the combination of two jaws hinged together at one end, a retaining-bar secured upon one of the jaws, a locking-lever journaled upon the other jaw consisting of two arms, one arm being cam-shaped to engage under the retaining-bar and the other being an actuating-arm for throwing the lever to clamp the jaws together. 80

2. In a clamp the combination of two jaws, one straight, the other curved, hinged together at one end and adapted to meet at the other end, a retaining-bar attached to the straight jaw, and a locking-lever fulcrumed upon the curved jaw, and having two arms, one an operating-arm and the other a cam-shaped arm 90 to engage under the retaining-bar to lock the jaws together.

3. In a clamp the combination of a straight and a curved jaw hinged together at one end and adapted to contact each other at the opposite end, both jaws being centrally slotted, a
5 retainer-bar secured upon the straight jaw over its slot, a fulcrum-pin secured upon the curved jaw over its slot, a locking-lever jour-

naled upon the pin and having a cam-shaped arm to engage under the retaining-bar and an actuating-arm.

FREDERICK MARGGRAFF.
